US00D995731S

(12) **United States Design Patent** (10) **Patent No.:** **US D995,731 S**
(45) **Date of Patent:** **** Aug. 15, 2023**

(54) **RADIATOR**

(71) Applicant: **Shenzhen Green Giant Energy Technology Development Co., Ltd., Shenzhen (CN)**

(72) Inventor: **Xiaoming Yang**, Shenzhen (CN)

(73) Assignee: **Shenzhen Green Giant Energy Technology Development Co., Ltd., Shenzhen (CN)**

(**) Term: **15 Years**

(21) Appl. No.: **29/873,217**

(22) Filed: **Mar. 28, 2023**

(51) LOC (14) Cl. **23-03**

(52) U.S. Cl.

USPC **D23/330; D14/447**

(58) **Field of Classification Search**

USPC **D23/330, 314, 332, 335, 336, 341; D14/432, 434, 447**

CPC **G06F 1/203**

See application file for complete search history.

(57) **CLAIM**

The ornamental design for a radiator, as shown and described.

DESCRIPTION

FIG. 1 is a front perspective view of a radiator, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is a rear perspective view shown in use thereof; and,

FIG. 10 is a partial enlargement of FIG. 1.

The broken lines in FIGS. 1 and 10 represent boundaries of the enlarged portions and form no part of the claimed design.
